United States Patent Office

Des. 204,564
Patented Apr. 26, 1966

204,564

PAIR OF SUNGLASSES

Walter C. Carmichael, West Peabody, Mass., assignor to American Optical Company, Southbridge, Mass., a voluntary association of Massachusetts

Filed May 19, 1965, Ser. No. 85,349

Term of patent 7 years

(Cl. D57—1)

FIG. 1 is a perspective view of a pair of sunglasses embodying my new design;

FIG. 2 is a top plan view thereof;

FIG. 3 is a front elevational view thereof; and

FIG. 4 is a side elevational view thereof.

The rear not shown conforms substantially in appearance to the front shown.

I claim:

The ornamental design for a pair of sunglasses, substantially as shown and described.
